US0D1065551S

(12) **United States Design Patent** (10) **Patent No.:** **US D1,065,551 S**
(45) **Date of Patent:** **** Mar. 4, 2025**

(54) **SKIN TREATMENT DEVICE**

(71) Applicant: **HYDRAFACIAL LLC**, Long Beach, CA (US)

(72) Inventors: **Daniel Harden**, Carmel, CA (US); **Elliot Ortiz**, Pinole, CA (US); **Yale Shaw**, San Francisco, CA (US); **Daniel Cheung**, San Francisco, CA (US); **Katie Rozporka**, San Jose, CA (US)

(73) Assignee: **HydraFacial LLC**, Long Beach, CA (US)

(**) Term: **15 Years**

(21) Appl. No.: **29/807,430**

(22) Filed: **Sep. 10, 2021**

(51) **LOC (15) Cl. 24-01**
(52) **U.S. Cl.**

USPC **D24/214**; D24/188

(57) **CLAIM**

The ornamental design for a skin treatment device as shown and described herein.

DESCRIPTION

FIG. 1 is a perspective view of a skin treatment device.

FIG. 2 is a front view of the skin treatment device of FIG. 1.

FIG. 3 is a rear view of the skin treatment device of FIG. 1. FIG. 4 is a left side view of the skin treatment device of FIG. 1.

FIG. 5 is a right side view of the skin treatment device of FIG. 1.

FIG. 6 is a top view of the skin treatment device of FIG. 1; and,

FIG. 7 is a bottom view of the skin treatment device of FIG. 1.

In the drawings, the broken lines depict portions of the skin treatment device that form no part of the claimed design.

1 Claim, 7 Drawing Sheets
